W. H. KEMPTON.
AUTOMATIC SECTION INSULATOR.
APPLICATION FILED JULY 13, 1910.

1,111,468.

Patented Sept. 22, 1914.

UNITED STATES PATENT OFFICE.

WILLARD H. KEMPTON, OF MANSFIELD, OHIO, ASSIGNOR TO THE OHIO BRASS COMPANY, OF MANSFIELD, OHIO, A CORPORATION OF NEW JERSEY.

AUTOMATIC SECTION-INSULATOR.

1,111,468.

Specification of Letters Patent. Patented Sept. 22, 1914.

Application filed July 13, 1910. Serial No. 571,687.

To all whom it may concern:

Be it known that I, WILLARD H. KEMPTON, a citizen of the United States, residing at Mansfield, in the county of Richland and State of Ohio, have invented certain new and useful Improvements in Automatic Section-Insulators, of which the following is a specification.

This invention relates to sectional trolley systems and switches therefor.

One object is to provide an improved construction, combination and arrangement of parts in switches for sectional trolley lines which switches will be simple and economical in construction, durable in service, and efficient in action.

Another object is to provide improved positive-action means for locking the switch in closed position when the section which it controls is in use.

A further object is to provide improved means for coöperatively disposing the locking means with respect to the trolley of a passing car.

Other and further objects will appear in the specification and be more specifically pointed out in the appended claims, reference being had to the accompanying drawings exemplifying the invention and in which—

Figure 1 is a side elevation of an insulating switch constructed in accordance with the principles of this invention. Fig. 2 is a top plan view of the same. Fig. 3 is a section on the line III—III of Fig. 1.

Referring now to Figs. 1, 2 and 3, the adjacent ends 19 and 20 of two successive sections of a sectional trolley system are provided with terminals 21 and 22, respectively, each of said terminals being provided with inwardly enlarging sockets 23 and 24, into which the wires 19 and 20 are respectively inserted and secured in position therein by suitable means, exemplified in the present embodiment by wedge-shaped blocks 25 and 26, each block being provided on one face with teeth or irregularities for gripping said wires. The terminals 21 and 22 form parts of a member common to both wires and which join the ends 19 and 20, but, which insulates them one from the other. Said member comprises with said terminals a central insulating portion 27 which is suspended from any suitable support by means

of a socket 28. The insulating portion, as clearly shown preferably comprises two flat plates or members of suitable insulating material, spaced apart, and between which at their end portions, the tongues 36 of the terminal members 21 and 22 are positioned. The insulating plates and tongues being solidly fastened together by any suitable means, such as clamping bolts passing through them. Pivottally and electrically connected with the terminal 21 is a switch lever 29 which swings about a pivot 30 at one end thereof into and out of circuit closing position with respect to the terminal 22. For this purpose said terminal 22 is provided with a rearwardly extending portion 31 provided with a knife contact adapted to coöperate with spring contacts 32 mounted on the outer swinging end of the switch lever 29. The switch lever 29 is provided below with a rounded portion 33, so that when it is moved into closed position, indicated by dotted lines in Fig. 1, it is adapted to form a continuous conductor across the gap between the ends 19 and 20 of the adjacent sections of the trolley system. A spring clip 34 is electrically connected to the terminal 21 by means of a flat plate 35 secured to a tongue 36 which forms a rigid portion of said terminal 21 and which is formed with an enlarged end 36' to engage with the insulating portions 27. A switch lever 29 is formed with lateral projections 37 which extend on both sides of the insulating portions 27, and are provided with perforations through which the pivot 30 extends, the bridging portion of the lever 29 being disposed below the insulating portion and having a slot 29' at the pivoted end into which a projection of the terminal 21 extends. One of the lateral projections 37 forms a knife plate for slidably engaging the spring clip 34 so that the electrical gap is bridged whenever the clip 32 engages the knife plate on the portion 31 of the terminal 22. In order to provide positive means for locking the knife lever 29 in circuit closing position, after the car has passed going in one direction, a detent 38 pivotally mounted at 39 eccentrically to its center of gravity, is adapted to fall into locking position shown in dotted lines in Fig. 1. A spring 40 is provided to make the action of the switch lever more positive; that is, it

5 prevents the switch lever from sticking in closed position when the detent 38 has been tripped by the passing trolley wheel, and prevents the switch lever 29 from accidentally closing. In order to provide means whereby the car returning in the opposite direction may open the switch 29, or permit said switch to be opened automatically, the detent 38 is provided with 10 a trigger portion 41, which, when the switch is in closed position and the detent in locking position, is disposed in the path of the trolley wheel, so as to be engaged thereby. Said detent is therefore lifted into the position shown in full lines in Fig. 1, leaving the switch 29 free to be returned to normal open circuit position shown in full lines under the action of its own weight and that of the spring 40.

20 What I claim is:

1. In a device for connecting and disconnecting adjacent sections of a sectional trolley wire or similar conductor, the combination with a normally open switch adapted to 25 be closed by a car passing in one direction, of means for locking said switch closed, said means being operable by a car passing in the opposite direction to permit the switch to resume its normally open position.

30 2. In a device for connecting and disconnecting adjacent sections of a sectional trolley wire or similar conductor, the combination with a normally open switch depending from one of said sections and adapted to be 35 closed by a car passing in one direction, of means automatically released by the closing of said switch for locking said switch, said locking means being provided with a part depending in the path of and operable by 40 the car returning in the opposite direction whereby the locking means is made inoperative and the switch permitted to return to open position.

3. In a device for connecting and disconnecting adjacent sections of a sectional trolley wire, the combination with a terminal member in electric connection with one section, of a switch pivoted thereon at one end 45 to normally depend in open position in the path of a trolley moving in one direction, of a detent for locking said switch in closed position, said detent being made operative when the switch is closed and provided with a trigger disposed to be engaged by the trolley moving in the opposite direction to release the switch.

4. In a device for connecting and disconnecting adjacent sections of a sectional trolley, the combination with a terminal for one 50 section, of a switch pivoted thereon to normally depend in the path of a trolley moving in one direction, a detent for said switch eccentrically pivoted to said terminal to drop into locking position under its own 55 weight when the switch is closed, said de-

tent being provided with a trigger in the path of said trolley on its return.

5. In a device for connecting and disconnecting adjacent sections of a sectional trolley wire, the combination with a terminal for one of said sections, of a switch pivoted thereon at one end to normally depend under its own weight in open position in the path of a trolley moving in one direction, means for locking the switch in closed position, a terminal connected to an adjacent section of the trolley line, spring contacts carried by the last mentioned terminal for co-operating with the free end of said switch, and means for forcing said switch into open position when it is released. 70

6. In a device of the nature described, the combination with adjacent ends of two insulated sections of a trolley line, of a non-conducting block disposed therebetween, terminals for said sections carried by said block, a switch pivotally and electrically connected with one of said terminals, a pair of contacts electrically connected to the other terminal and adapted to co-operate with said switch, a detent mounted on the first terminal for holding the switch in engagement with said contacts, said detent being operable by a passing trolley to release the switch, and resilient means for throwing said switch away from said contacts 80 when the switch is released. 85

7. In a device of the character described, the combination with two adjacent sections of a sectional trolley system, of a terminal member connected with each of said sections and means insulating said terminal members from each other, said members being provided with sockets for the reception of the ends of said sections, said sockets being 90 enlarged inwardly, a wedge fitting the enlarged portion of each socket and engaging the end of each trolley section, and a switch pivotally mounted on one of said terminal members and in electric connection with one 95 of said sections, said switch being operable by a passing car to close the gap between said sections. 100

8. In a device of the character described, the combination with the contiguous ends 105 of two conductors, of a terminal secured to each conductor, said terminal being provided with an enlarged extremity, and a pair of non-conducting members provided with recesses adapting them to fit around 110 the extremities of said terminals and to engage the enlarged portions thereof. 115

9. In a device of the character described, the combination with the contiguous ends 120 of two conductors, of a terminal secured to each conductor, said terminal being provided with a tongue having an enlarged outer end, a pair of blocks of non-conducting material and provided with recesses 125 adapting them to fit closely about the 130

tongues of said terminals, and means for securing said blocks together to clamp said tongues therebetween.

10. In a device of the character described, 5 the combination with the contiguous ends of two conductors, of a terminal secured to each conductor, said terminal being provided with a tongue having an enlarged outer end, a pair of blocks of non-conducting material and provided with recesses adapting them to fit closely about the tongues of said terminals, and a plurality of bolts for securing said blocks together to clamp said tongues therebetween, said terminals being provided with integral transverse plates covering the ends of said blocks.
11. In a device of the character described, 15 the combination with the contiguous ends of two conductors, of a terminal secured to each conductor, said terminal being provided with a tongue having an enlarged outer end, a pair of blocks of non-conducting material and provided with recesses adapting them to fit closely about the 20 tongues of said terminals, a plurality of bolts for securing said blocks together to clamp said tongues therebetween, and means for suspending said blocks, connected to one of said bolts.
- 30 12. In a circuit breaker, a plate of insulation, trolley wire holders carried by the ends thereof, a knife switch for establishing an electrical connection between said holders, and a shoe carried by the blade of said 35 switch to bridge the gap between said holders.

13. In a circuit breaker, a plate of insulation, trolley wire holders carried by the ends thereof and providing a gap centrally of the 40 lower edge of said plate, a switch blade pivotally connected to one of said holders, contact arms carried by the other holder to receive said blade and establish an electric connection between said holders, and a shoe 45 carried by said blade and adapted to bridge the gap between said holders.

14. In a circuit breaker, trolley wire 50 holders providing a gap, a knife switch adapted to provide an electrical connection between said holders, and a shoe carried by

the blade of said switch to bridge the gap between said holders.

15. In a device of the class described, 55 trolley wire holders provided with a gap, a pivoted switch adapted to provide an electrical connection between said holders, and a bridging shoe carried by the blade of said switch to bridge the gap between said holders.

16. In a device of the class described, 60 the combination of two terminal members to which the ends of the trolley wires are adapted to be attached, insulating means spacing said terminal members apart to provide a gap therebetween, a switch member 65 for electrically connecting said terminal members, and means carried by said switch member for mechanically bridging said gap, said means being substantially flush with said terminal members to permit the trolley 70 to pass said gap.

17. The combination of a pair of terminal members to which the ends of the trolley wire are adapted to be attached, said members having under run surfaces forming substantially a continuation of the trolley wire, 75 insulating means spacing said terminal members apart to form an open gap between said members, a switch member for electrically connecting said terminal members, and means adapted to be positioned in the gap when said switch is operated to provide a mechanical bridge in the gap over which the trolley may run.

18. The combination of two members insulated from each and spaced apart to form an open gap, a movable member adapted to be moved into said gap to provide a surface along which the trolley member may run from one member to the other without interruption, and means operable when said member is moved into said gap for electrically connecting said terminal members. 80 90

In testimony whereof I have signed my name to this specification.

WILLARD H. KEMPTON.
